WILLOUGHBY F. HILL, OF MAMARONECK, NEW YORK

PROCESS FOR THE PRODUCTION OF PAPER CUPS

Application filed March 20, 1928. Serial No. 283,213.

My invention relates to processes for the production of paper containers and refers particularly to cup-shaped paper containers having rolled rims.

In the production of paper cups of this character a disc of suitable paper, cut from a sheet of any suitable cutting machine, is passed through crimping and cup-forming machines, whereby the cup is formed, the 10 sides of the cup are crimped and the rim portion rolled to form a strong supporting edge for the device.

For cups intended for retaining liquids, the employed paper must be comparatively 15 impervious to liquids and for such cups a paper treated with paraffin or other suitable material is used.

For purposes of utility it is necessary to employ a strong thin paper, and as the several processes through which it passes during 20 the cup production are liable to tear, or rupture it, it is essential that these operations be of such a character as to avoid these injurious results.

I have found that the edge-rolling step of 25 process can be executed more advantageously, both as to ease of production and superiority of produced results, if the edge to be rolled is moistened before being subjected to the rolling process.

I have further found that if the central portion of the paper disc be moistened it cannot be successfully submitted to the cup forming process as it will tear and will not 30 pass through the cup forming machine successfully.

One of the objects of my invention is the 35 step of process which allows of the moistening of a sufficient portion of the outer edge of the disc while maintaining the inner portion of the disc from objectionable moistening.

Another object of my invention is to treat 40 the paper before cutting into discs with an electric prohibitive substance which will prevent the formation of frictionally formed electricity during the disc cutting operation.

In order that devices of this character may 45 be economically manufactured it is necessary that they be made in mass production, and

hence, a successful method must be one which will allow of rapid manipulation of the devices during their production, which advantageous and valuable attribute is possessed by the process of my invention.

In the accompanying drawings illustrating 55 the following of the process of my invention, similar parts are designated by similar numerals.

Figure 1 is a top view of a pile of prepared 60 sheets having the discs cut therein.

Figure 2 is a section through the line 2—2 of Figure 1.

Figure 3 is a top view of a pile of discs with water-proof discs added thereto.

Figure 4 is a section through the line 3—3 of Figure 4.

Figure 5, 6, 7 and 8 show modified forms of rolled edges of devices made according 70 to my invention.

One particular method of my invention is as follows:—

The paper in the form of rolls or sheets is treated upon one or both sides with a substance which acts in the nature of an electric 75 prohibitive to reduce the danger of frictionally formed electrical conditions during the process of crimping and forming and which also acts to render the cup impervious to moisture, and among such substances I have found 80 paraffin to be particularly suitable, although I do not limit myself to this particular product.

A number of sheets, say about 500, are then placed upon each other and a disc of the desired size cut from all of the sheets in the pile at the same time, thus forming a vertical stack of a large number of discs all of the same size.

I then place a water proof disc of suitable 90 material upon the top and under the bottom of the stack and submit it to an atmosphere, the humidity point of which is quite high, the atmosphere containing enough moisture to deposit the same upon the exposed edges of 95 the stacked discs. The amount of humidity is dependent upon the character of the paper employed and the length of time of treatment and a suitable non-poisonous disinfectant may be employed with the moisture if desired. 100

The discs are retained in the humidifying atmosphere until the moisture has penetrated the discs a sufficient distance from the exposed edges dependent upon the character of the cup to be produced.

5 The discs are then removed from the humidifying atmosphere and while still moist are subjected to crimping, cup-forming and edge rolling operations.

10 Figure 1 shows a top view of a plurality of sheets of paper 10, 10 piled upon each other, from which a plurality of piles of discs 11, 11 have been cut. A water proof disc 12 is placed upon the pile of discs 11, 11 and a 15 water-proof disc 13 is placed below the pile. When submitted to a humidifying atmosphere, the edge portions 15, 15 of the discs become moistened. The central portion of each disc is thus retained in a dry condition 20 to a low it to be molded by a die into the bottom 16 and side 17 of a cup, while the moistened edge portion is in condition to be rolled. Figures 5, 6, 7 and 8 show modified forms of 25 rolled edges, 18, 19, 20 and 21, but as my invention is not directed to any particular form of rolled edges, those shown are given simply as examples, without limiting myself to this particular formation.

It will thus be seen that by the process of 30 my invention, the discs are properly moistened for edge-rolling purposes while maintaining the central portions thereof in dry condition for crimping and cup-forming and that this moistening step is applied simultaneously to a large number of discs.

In some cases I have found it advisable to surround the stack of paper discs with a moistened cloth while in the humidifying atmosphere in order to obtain the proper quantity of peripheral moisture.

40 By "proper discs" in my specification and claims I mean discs of paper both treated and untreated with electric prohibitive substances.

45 My invention, therefore, presents a great advancement in the art of making paper containers of the character described and allows of their rapid, effective and successful production.

50 I do not limit myself to the particular size, shape, number or arrangement of indicated parts or to the particular sequence of steps of operation as these are given simply as a means for clearly describing my invention.

55 What I claim is:—

1. In a process for the production of paper cups having rolled edges, the step which comprises treating a plurality of paper discs to a humidifying atmosphere, whereby the peripheral portions of said discs will be moistened and the central portions of said discs will be protected against said moistening effect.

60 2. In a process for the production of paper cups having rolled edges, the step which com-

prises treating a plurality of superimposed paper discs to a humidifying atmosphere, whereby the peripheral portions of said discs will be moistened and the central portions of said discs will be protected against said moistening effect.

75 3. In a process for the production of paper cups having roller edges, the step which comprises simultaneously subjecting the edges of a plurality of superimposed paper discs to moisture.

80 4. In a process for the production of paper cups having rolled edges, the step which comprises simultaneously subjecting the edges of a plurality of superimposed paper discs to a humidifying atmosphere.

85 5. In a process for the production of paper cups having rolled edges, the step which comprises simultaneously subjecting the edges of a plurality of superimposed paper discs to moisture and a disinfectant.

90 6. In a process for the production of paper cups having rolled edges, the step which comprises simultaneously subjecting the edges of a plurality of superimposed paper discs to a humidifying atmosphere and a disinfectant.

95 7. In a process for the production of paper cups having rolled edges, the steps which comprise placing a number of sheets of paper upon each other, cutting discs from the thus superimposed sheets and subjecting the thus formed stack of discs to a humidifying atmosphere.

100 8. In a process for the production of paper cups having rolled edges, the steps which comprise placing a number of sheets of paper upon each other, cutting discs from the thus superimposed sheets and subjecting the edges of the thus formed stack of discs to moisture.

105 9. In a process for the production of paper cups having rolled edges, the steps which comprise placing a number of sheets of paper upon each other, cutting discs from the thus superimposed sheets and subjecting the thus formed stack of discs to a humidifying atmosphere and a disinfectant.

110 10. In a process for the production of paper cups having rolled edges, the steps which comprise placing a number of sheets of paper upon each other, cutting discs from the thus superimposed sheets and subjecting the edges of the thus formed stack of discs to moisture and a disinfectant.

115 11. In a process for the production of paper cups having rolled edges, the steps which comprise placing a number of sheets of paper upon each other, cutting discs from the thus superimposed sheets, subjecting the thus formed stack of discs to a humidifying atmosphere, crimping and cup-forming each said disc and rolling the edge of each said cup.

120 12. In a process for the production of paper cups having rolled edges, the steps which comprise placing a number of sheets of paper

upon each other, cutting discs from the thus superimposed sheets, subjecting the edges of the thus formed stack of discs to moisture, crimping and cup-forming each said disc and rolling the edge of each said cup.

5 13. In a process for the production of paper cups, the step which comprises treating sheets of paper with an electric prohibitive substance, stacking the sheets and cutting a plurality of discs from the thus stacked sheets of paper.

10 14. In a process for the production of paper cups having rolled edges, the steps which comprise treating a number of sheets of paper with an electric prohibitive substance, placing a number of such sheets upon each other, cutting discs from the thus superimposed sheets and subjecting the thus formed stack of discs to moisture.

15 15. In a process for the production of paper cups having rolled edges, the steps which comprise treating a number of sheets of paper with an electric prohibitive substance, placing a number of such sheets upon each other, cutting discs from the thus superimposed sheets, subjecting the thus formed stack of discs to moisture and a disinfectant.

20 16. In a process for the production of paper cups having rolled edges, the steps which comprise treating a number of sheets of paper with an electric prohibitive substance, placing a number of such sheets upon each other, cutting discs from the thus superimposed sheets, subjecting the thus formed stack of discs to moisture, crimping and cup-forming each said disc and rolling the edge of each said cup.

25 Signed at New York City in the county of New York and State of New York this 19th day of March, 1928.

30 WILLOUGHBY F. HILL.
